LIQUEFIED PETROLEUM GAS SYSTEM

John R. Holicer, Shreveport, La.

Application July 12, 1941, Serial No. 402,255

6 Claims. (Cl. 62—1)

This invention relates to a liquefied petroleum gas vaporizer.

An object of the invention is to provide a gas vaporizer of the character described specially designed for utilizing liquefied petroleum gas as a fuel.

The vaporizer is constructed as an independent unit for use where natural or artificial gas is not available and which is designed to utilize butane or other liquefied petroleum gas.

Another object of the invention is to provide, in a vaporizer of the character described, novel means of causing the vaporization of the liquid into a gas as it flows from the storage tank through the dispensing apparatus.

Vaporizers of this general type embody a storage tank and dispensing apparatus for delivering the vaporized gas to the point of utilization. It is common practice to bury the storage tank beneath the surface of the earth and to mount the dispensing equipment thereon. When the tank is buried in the earth it rapidly deteriorates and must from time to time be renewed. By the use of the present invention the storage tank may be located above the surface of the earth with only the dispensing equipment buried in the ground and this dispensing equipment may be made of durable material which will not readily deteriorate and will therefore not need to be often renewed or replaced. Furthermore, with the storage tank placed above ground and with the dispensing equipment buried in the earth, vapor of substantially uniform B. t. u. will be delivered irrespective of the temperature or pressure of the gas in the storage tank.

Another object of the invention is to provide in a gas vaporizer of the character described an auxiliary storage chamber, or gas collector, associated with the dispensing apparatus which will collect a portion of the vapor being delivered, and in case of overload will store the liquid entrained in the vapor with an automatic cut-off and expansion valve arranged to be closed by the liquid rising in the auxiliary storage tank or collector. The arrangement is such that while the automatic cut-off and expansion valve is closed, fuel will be continued to be supplied to the point of utilization by the vaporization of the liquid in the auxiliary storage tank or collector.

Another object of the invention is to provide in a vaporizer of the character described, novel means for causing the vaporization of the gas as it flows from the storage tank through the dispensing apparatus.

With the above and other objects in view the

invention has particular relation to certain novel features of construction, operation and arrangement of parts, examples of which are given in this specification and illustrated in the accompanying drawings, wherein:

Figure 1 shows a side elevation of the vaporizer, partly in section, and showing the storage tank partly broken away.

Figure 2 shows a fragmentary, vertical, sectional view of the hood employed.

Figure 3 shows a fragmentary, longitudinal, sectional view of the automatic cut-off and expansion valve assembly.

Figure 4 shows a side view, partly in section, of the valve employed in said assembly.

Figure 5 shows a sectional view taken on the line 5—5 of Figure 3.

Figure 6 shows a vertical, sectional view of the regulator.

Figure 7 shows a vertical, sectional view taken on the line 7—7 of Figure 6, and

Figure 8 shows a side elevation, partly in section, of the auxiliary storage tank, or collector, illustrating another embodiment of the invention.

Referring now more particularly to the drawings wherein like numerals of reference designate the same parts in each of the figures, the numeral 1 designates the storage tank which, in the present illustration, is shown located above the surface of the ground on the foundation 2. A feed pipe 3 leads from the tank 1 and is equipped with a shut-off valve 4 and a regulating valve assembly 5. The regulating valve assembly is shown in detail in Figures 6 and 7. It is of conventional construction and need not be described in specific detail. It has an inlet duct 6 whose inner end is downwardly turned and may be closed by the valve 7. This valve is connected to the transverse diaphragm 8 and a strong coil spring 9 normally acts against said diaphragm to hold the valve 7 open to allow the flow of liquid through the inlet duct 6 and said liquid then passes into the chamber 10 beneath said diaphragm and out through the outlet duct 11 and on through the line 3.

The coil spring 9 is enclosed by means of an adjustable nut 12 having a threaded connection with the valve casing whereby the compression of the spring 9 may be varied.

The liquid flowing out from the tank 1 will be under the pressure of the vaporized gas accumulating in the tank 1 and as the pressure rises it will act against the diaphragm 8 to overcome the pressure of the spring 9 and close the

valve 7. The flow of liquid through the feed line 3 to the dispensing apparatus is thereby controlled. In the embodiment illustrated in Figure 1, the feed line 3 is formed into a coil 13 preferably composed of copper tubing. The numeral 14 designates a stand pipe forming an auxiliary reservoir or gas collector. This collector is closed at its upper and lower ends by the upper and lower end plates 15, 16 which may be welded thereto. The coil surrounds said stand pipe and may be clamped thereto by the clamp 17.

The coil 13 terminates in a cylindrical valve casing 18 preferably formed of brass and which is screwed into an outwardly extended nipple 19 carried by the stand pipe 14. The valve casing 18 has an axial channel 20 which terminates, at its inner end, at the valve seat 21. This channel merges into an enlarged axial bore 22 in said valve casing in which the cylindrical plunger valve 23 is slidably mounted. The bore 22 has the longitudinal channels 24 extending to the inner end of the valve casing 18 and through which the vapor may pass around the plunger valve 23.

The inner end of the valve 23 has a deep slot 25 and also has a cross pin 26 extending across said slot.

There is a toggle lever 27 having a depending extension 27a. The extension 27a works in a slot 28 in the inner end of the valve casing 18 and is pivoted therein on the cross pin 26. The upper margin of the toggle lever 27 is provided with a notch 30 to receive the cross pin 26. Extended inwardly from the inner end of the lever 27 there is a rod 31 to the inner end of which the float 32 is attached. This float is located in the upper end of the auxiliary tank or gas collector formed by the stand pipe 14 and when the vaporizer becomes overloaded, that is when the consumption of fuel exceeds the capacity of the vaporizer liquid will collect in said gas chamber or collector and will lift the float into the position shown in Figures 1 and 3; the plunger valve 23 will be closed; that is, it will be moved against the seat 21 to temporarily prevent the further admission of vapor from the coil 13. The outer end of the valve 23 has an insert 33 of neoprene or similar material countersunk therein to make a close fitting joint with the seat 21 when the valve is closed.

As the level of the liquid in the collector descends the float 32 will also descend to open the valve 23 to permit resumption of the flow of vapor from the coil 13.

In the embodiment illustrated in Figure 8 the feed pipe 3 is connected directly into the outer end of the valve casing 18, the coil 13 being dispensed with as under certain conditions this coil may be found not necessary.

Mounted on the upper end of the stand pipe 14, by suitable brackets 33 there is a cylindrical upstanding hood 34. This hood is equipped with a removable cover 35. As shown the dispensing equipment and the hood are buried in the ground with the removable cover 35 accessible above the ground surface.

Chamber 14 is provided with a relief valve 37 located within the hood 34. This relief valve may be directly connected to plate 15, and have thereabove a vent pipe 36.

Leading out from said collecting chamber beneath the top plate 15 there is a service pipe 38 which continues through the hood 34 and continues on to the point of utilization. Incorporated in this service pipe and located within the hood there is a conventional pressure regu-

lator 39 which is equipped with the upstanding vent pipe 40 located within the hood and whose upper end may be downwardly turned, if desired, as shown in Figure 2.

5 The liquid will flow from the tank 1 through the delivery line 3 passing through the regulating valve assembly 5 and will expand and become partially vaporized as it passes through the line 3. The vaporization will continue as the fluid passes through the coil 13, said coil being of a sufficiently high temperature, from the earth, to cause said vaporization. The float 32 will normally be in its lower position with the valve 23 open so that the vapor will readily pass into the stand pipe and thence out through the service line 38, the flow of gas being controlled by the regulator 39. The operation will be the same with the embodiment shown in Figure 8 which will be used under conditions not requiring the coil 13.

20 The liquid entrained in the gas entering the auxiliary tank, or standpipe 14, will drop down in case of an overload into said tank, the tank acting as a collector. Should a sufficient amount of liquid be collected in the collector to lift the float 32 the valve 23 will be thereby closed to temporarily cut off the delivery of fuel from the coil 13, or the delivery pipe 3 of Figure 8. While the valve 23 is closed the liquid in the auxiliary tank 14 will vaporize sufficiently to furnish a supply of gas through the service line 38 until the level of the liquid in the auxiliary tank 14 has fallen to allow the valve 23 to open whereupon a normal delivery of gas from the tank 1 will be resumed.

25 The auxiliary supply tank is provided with a drain opening at its lower end which is normally closed by the plug 41.

The drawings and description are illustrative 30 merely while the broad principle of the invention will be defined by the appended claims.

35 There has been filed in the Patent Office applicant's co-pending application, filed June 29, 1943, under Serial No. 492,738, for "Method and apparatus for storing, atomizing and generating liquefied petroleum gases," which is considered 40 as an improvement over this instant invention, and cross-reference thereto is here made.

45 What I claim is:

50 1. In a system for vaporizing liquefied petroleum gas, a storage tank arranged above the ground surface, a collector arranged beneath the ground surface, a fluid conducting line leading from the tank into the upper portion of the col-

55 lector, a regulating valve incorporated into said line, float means movable in accordance with the level of the liquid in the collector to control the flow of fluid through the line, a service line leading from the collector, a regulator for controlling 60 the flow of fluid through the service line and a hood mounted on the collector and enclosing the regulator.

65 2. Apparatus of the character described for storing and vaporizing liquefied petroleum gas, comprising a storage tank, a collector, a fluid conducting line leading from the tank into the collector and formed into a coil about the collector, a valve for controlling the flow of fluid into the collector from said line, a float movable 70 in accordance with the level of the liquid in the collector for opening and closing the valve and a service line leading from the collector.

75 3. Apparatus of the character described for storing and vaporizing liquefied petroleum gas, comprising a storage tank, a collector beneath the

level of the storage tank, a fluid conducting line leading from the tank into the top of the collector, a regulating valve incorporated in said line, means including a float in the collector for opening and closing the line, a service line leading out from the upper portion of the collector, a regulator for controlling the flow of fluid through the service line and a hood on the collector enclosing the regulator.

4. In apparatus for vaporizing and dispensing liquefied petroleum gas, a collecting and vaporizing chamber buried in the earth; a valve associated therewith for controlling the delivery of fluid thereto; said valve being provided with a casing having an axial channel terminating, at its inner end, in a valve seat, said casing having an enlarged axial bore into which the channel merges, said bore having longitudinal wall channels, a cylindrical valve plunger mounted in the bore and having one end arranged to co-act with the seat to close and open said axial channel, a toggle lever pivoted to said plunger and having a depending extension pivoted to the casing; and a float connected to the free end of the lever.

5. In a system for vaporizing liquefied petroleum gas, a fixed storage tank arranged above

the ground surface, a vertical standpipe arranged beneath the ground surface and forming a collector to provide a float chamber, a fluid conducting line leading from the tank and terminating in the float chamber, a regulating valve incorporated into said line, a float moveable in accordance with the level of the liquid in the chamber to control the flow of fluid through the line, a service line leading from the standpipe above the float, a regulator for controlling the flow of fluid through the service line and located beneath the ground surface, a hood mounted on the upper end of the standpipe and enclosing the regulator.

6. In apparatus for vaporizing and dispensing liquefied petroleum gas, a storage tank under pressure; a collecting and vaporizing chamber buried in the earth; a pipe for conducting fluid from the tank to the chamber; means adapted to limit the pressure of the fluid delivered to the chamber; an expansion valve associated with the chamber and adapted to expand the fluid delivered thereto; a gas service pipe leading from the chamber; and a pressure regulator carried by the service pipe.

JOHN R. HOLICER.
